TRANSFORMER

John Herold Bridges, Paterson, N. J., assignor,
by mesne assignments, to National Inventions
Corporation, a corporation of New Jersey

Original application June 25, 1942, Serial No.
448,471. Divided and this application August
12, 1943, Serial No. 498,345

4 Claims. (Cl. 171—119)

1

My application is a division of my co-pending application Serial No. 448,471, filed June 25, 1942, entitled Luminescent Tube System, now Patent 2,370,635 of March 6, 1945, and the invention relates to fluorescent lighting equipment, and more particularly concerns a new transformer power unit and associated system, for powering fluorescent space discharge tubes.

An object of my invention, therefore, is to produce a simple, compact, sturdy, reliable and inexpensive transformer, having high leakage reactance, characterized by the small iron content required, its low operation and maintenance costs, and its good voltage regulation.

Another object is to produce an autotransformer embodying all of the advantages set forth in the foregoing, and the windings of which are disposed in the smallest possible compass.

A still further object is to produce a new fluorescent tube lighting system embodying a transformer power unit having the advantages described, and possessing the qualities of quick striking, long tube life, steady tube operation in the substantial absence of detrimental flicker even during cold weather operation, the substantial elimination of undesired stroboscopic effect, and high system power factor.

Other objects and advantages will in part be obvious and in part pointed out hereinafter.

My invention, accordingly, resides in the several elements, features of construction, and operational steps, and in the relation of each of the same to one or more of the others, all as described herein, the scope of the application of which is indicated in the claims at the end of this specification.

In the drawings, Figure 1 is a schematic elevation of a transformer and attendant system embodying the principles of my invention.

Figure 2 depicts the electrical circuits according to my invention; while

Figures 3 and 4 are graphs illustrating wave forms on the condensive and inductive sides, respectively, of the system according to my invention; and

Figure 5 illustrates a modified embodiment of my invention.

To facilitate more thorough understanding of my new transformer and system, it may be noted that the illumination art has come more and more to accept fluorescent tube lighting as a customary and desirable expedient in a number of widely diversified fields involving both general and specialized illuminating problems. Many factors contribute to this rapid acceptance of

fluorescent lighting. Among them may be cited, simply by way of illustration and by no means intended as exclusive, the high lighting efficiency of such tubes for unit power input, whereby maximum light output can be achieved at a minimum of cost; as well as the low temperatures at which such tubes operate, whereby in entirely practical manner, high intensity lighting of comparatively low brilliance can be achieved in enclosed spaces.

Because of the economies of such fluorescent lighting from a power standpoint, it makes entirely feasible, for the first time, the use of adequate lighting for advertising and other purposes, in those cases where for economic reasons, adequate illumination was hitherto impossible. The economy of such lighting is contributed to by the long life of the fluorescent tube, which at the present time, is rated at between 2 to 2½ times longer life than are the best grade of incandescent lamps now on the market.

The active light emission region of these tubes being long as compared to the light source in incandescent bulbs produces an intense but diffused light of low brilliance which lends itself admirably to flood light effects. It is entirely possible, because of the low operation costs and the low temperatures at which the tubes operate, to employ them in batteries of two, three, four, or more tubes. Thus arranged, they may be employed in extremely satisfactory flood lighting displays. Their use has become widespread in both indoor and outdoor fields where daylight conditions must be approximated, as for example, in factories, filling stations and the like.

It is possible to vary the characteristic color of particular tubes within wide limits to satisfy the particular lighting problem in question, simply by employing different fluorescent salts or phosphors as liners for the tubes, the particular visible secondary radiation of such salts having previously been determined and calibrated by experiment. It is this feature, widely at variance with the substantially fixed quality of radiation available from the known filamentary lamp, which has constituted an important factor contributing to the present-day widespread use of fluorescent lighting in advertising, store and household lighting.

Despite, however, the rapid growth of fluorescent tube lighting practice, to its present day important position in the illumination field, many defects, serious from a practical standpoint, remain to be removed before fullest exploitation of such equipment can be undertaken.

To illustrate, for example, heretofore such

2

fluorescent tubes have been designed for operation across ordinary 110 volt or 220 volt service lines. Difficulty is encountered, however, in that these low voltage tubes do not start with any degree of facility on the ordinary service potentials. Consequently, it frequently becomes necessary to equip them with an additional starting electrode, and in all instances a starting switch must be supplied for each such low potential tube. Such switches ordinarily take one of three conventional forms: the magnetic relay, the thermal, or the glow-discharge type. All of these switches are found to be comparatively slow in starting, requiring about six seconds on the average to strike the arc, while in the glow-discharge type of switch, difficulty is experienced in quickly re-striking the arc, once it has extinguished for any reason, after being initially struck.

Additionally, where several tubes are operated in parallel, a starting compensator is found to be required, disposed in series circuit with that tube of leading current demand, to ensure that sufficient voltage is applied initially to strike the arc across that tube. Finally, these arc discharge tubes have negative resistance characteristics, by which is meant that once the arc is struck, the resistance of the discharge path thereacross will decrease to such extremely small value that unless adequate current-limiting means are provided, the current across the arc will increase to a prohibitive value, either destroying the tube load or burning out or interrupting the electrical energy supply thereto. In low-voltage tube systems essential current-limiting means usually takes the form of an ohmic resistance on the less expensive installations, or of an iron-core choke coil in the more costly units.

All of these auxiliaries, as they are called, require complicated and expensive installation technique and demand many electrical connections. Their large number of auxiliaries for a battery or bank of tubes results in a bulky assembly, neat appearance of the complete assembly and simplicity in installation being difficult, indeed, well-nigh impossible to achieve. Each such auxiliary separately constitutes a potential source of disturbance in the system and is subject to getting out of order or failure, giving rise to attendant maintenance or repair costs. Too, it is evident that although the cost of each auxiliary may in itself be a comparatively small item, nevertheless when it is considered that it is customary to employ such tubes in banks or batteries of two or more, and that despite this, each tube still requires its own complement of auxiliaries, it is at once evident that the total cost cannot escape being high.

Furthermore, the comparatively small iron content of the iron core ballasts and the absence of iron in the ohmic resistors, result in poor voltage regulation, so that the tube equipment is extremely sensitive to variation in line voltage.

The low terminal voltage at which these hot cathode tubes are operated gives rise to the series disadvantages in cold weather operation of either detrimental flicker, or in extreme cases, of extinguishment of the arc. For like reason, it is difficult or even impossible, where low-potential, hot-cathode tube equipment is employed, to strike the arc initially when extremely cold weather conditions prevail. This undesirable phenomenon is attributable to the fact that the striking potential of the tubes is close to the peak voltage obtainable from the ordinary service

mains, whereby no reserve of impressed voltage is present to accommodate even slight increase over rated value of the striking potential of the arc.

5 Experience demonstrates that hot-cathode tubes employed in hot-cathode operation in low-voltage systems are comparatively short-lived, this short life being contributed to by a number of causes. Among them may be listed by way of 10 illustration, the inherent fragility of the incandescent filaments employed. It is well-recognized to be characteristic of such filaments that in operation, the arc tends to settle locally at one point thereon, usually the high voltage 15 end. Burning follows, shortly attended by failure of the electrode, whereupon the tube displays rectifier action, attended by continuous flicker and usually followed by early failure of the other electrode.

20 Additionally, reliance is placed in striking the arc across these low-voltage, hot-cathode tubes, on copious emission of electrons from the electrodes thereof. To this end, the electrodes are customarily coated with a suitable electron-emitting 25 substance, usually a suitable oxide. During operation, however, this electron coating is gradually dissipated, so that for this, as well as for the other reasons set forth hereinbefore, the low-voltage, hot-cathode tubes do not display the 30 long life which is desirable in this art.

Considerable research has been carried out by various workers skilled in the art, looking for one or more solutions for the various problems set forth in the foregoing. Among the more important 35 developments, that of materially increasing the terminal voltages at which the fluorescent tubes are energized, at the same time employing them in cold-cathode operation, is outstanding. It has been proposed that those 40 elevated voltages be transformed directly through the intermediary of a transformer from service mains of conventional voltage rating, such as 110 or 220 volts.

45 For such transformer system operation, either a specially designed cold-cathode tube or an adapted hot-cathode tube is employed. Hot-cathode tubes, which are readily available on the market, are conveniently adapted for cold-cathode operation simply by short-circuiting the terminals of the electrodes thereof to ensure that all portions of a particular electrode are maintained at the same potential. It was found that by observing proper precautions in the operation of these hot-cathode tubes on cold-cathode operation, they display great ruggedness, and their effective lives are prolonged considerably over 50 what had hitherto been experienced.

To economize on both space and materials required, and in general to reduce production cost to a minimum, recourse preferably has been had to autotransformer equipment. Up to the limiting voltage permitted by the Fire Underwriters, such transformer equipment is entirely satisfactory, although slightly higher in first cost than 60 is the conventional hot-cathode tube lighting unit, including its necessary auxiliaries. The sturdiness of such equipment and the small amount of attention and supervision required thereby make its total cost, including maintenance, only a little, if any, greater than the comparable cost of the hot-cathode equipment. When such transformers are employed, either as single or double transformers, i. e., transformers having one or two separate secondaries, to 65 energize banks of two, three or more tubes, then 70 75

the absence of the hitherto all-essential auxiliaries is found to bring the unit cost to a value lower than that of the hot-cathode tubes.

It is not sufficient, however, simply to interpose a transformer between the line and the fluorescent tube load, because such ordinary transformer, either with simple or autotransformer connection, does not provide sufficient impedance to prevent enormous build-up of current and voltage across the secondary, once the arc across the tube is struck. On the other hand, if recourse be had to auxiliaries to ballast the tubes, then one of the main purposes of employing transformer energization means, namely, keeping the over-all cost to a minimum, would be defeated. This difficulty has been alleviated by providing in the iron core of the transformer, between the primary and secondary windings, high leakage reactance shunts. These shunts normally have no effect when the secondary windings are de-energized, so that substantially all of the primary flux from the primary winding courses along the main magnetic path or paths, interlinking the secondary winding or windings. However, when the arc strikes across the load consisting of one or more tubes, changing the reluctance of the main flux path, these shunts then display a reluctance lower than that of the main magnetic path. This change in reluctance of the main magnetic path results from the back magneto-motive force set up by the energized secondary winding. The main stream of primary flux then courses across these high reluctance magnetic shunts, with their included air-gaps, the calibration of the shunts being such that just sufficient primary flux interlinks the secondary winding or windings to induce a voltage and current therein sufficient to maintain the arc across the tube load.

Such new tube lighting equipment, consisting of a transformer fluorescent tube lighting system and associated power unit, displays many extremely important and thoroughly practical advantages as contrasted with the lower voltage, hot-cathode tube lighting units theretofore employed. The arc across the tube displays quick striking characteristics, and can readily be re-struck, should it momentarily extinguish for any reason. The number of parts is reduced to a minimum. A far smaller number of external connections is required than had hitherto been the case. The power unit is simple and of small size. The sturdiness of the lighting unit, even with outdoor use and while subjected to severe weather conditions, is found to be outstanding.

The higher rated voltages make it entirely feasible, from a practical standpoint, to operate the tubes under "dimmer" conditions, i. e., at primary terminal voltages which are lower than the rated terminal voltages. The higher secondary voltages, substantially in excess of the striking potential of the tube, permit a reduction in the secondary voltage, while still maintaining the peaks of the second voltage wave form substantially in excess of the striking potentials of the tubes. When so operated, the period during which the arc remains energized across the tube during each current half-cycle is decreased, so that the total quantity of light per unit of time is diminished, thus giving rise to the "dimmer" action referred to.

Many further refinements and improvements upon the transformer-powered cold cathode fluorescent tube lighting systems of the type described, however, remain to be accomplished, be-

fore the full field of utilization of this equipment can be exploited. For example, while the life of the tubes employed in transformer-powered units of the type described is satisfactory, measured on an absolute basis, the results nevertheless are somewhat disappointing in that this life is not quite as great as appears to be indicated, from theoretical considerations. The decrease in tube life, determined experimentally, from the anticipated ideal value constituted a most perplexing problem, no satisfactory solution for which was brought forward for a considerable time span. Finally, however, it was discovered that the double transformer, which had been used in so many lighting systems to achieve economies therein, was probably at fault. The combination of capacitative and inductive reactances, constituted by the tube load and secondary winding, frequently produces resonance effects in one or both secondaries which are then transmitted through the auto-connected primary winding to the other secondary winding, creating disturbances and surges therein. The effect is cumulative and reciprocal, so that after the passage of a number of current cycles, extremely high resonating and transient voltages are built up, which particularly display themselves at the moments of striking and extinguishment of the arc during each current half-cycle. These high voltages have very disturbing effects on the tube, decreasing the life thereof appreciably, sputtering the electrode materials and destroying the electrodes themselves, depositing the sputtered electrode material on the walls of the tube so as to coat the fluorescent lining thereof serving as a trap in which to occlude the gas content of the tube, resulting in "hardening" of the tube, decreasing the electrode emissive qualities of the sputtered electrode, and perhaps eventually destroying either the tube or the associated equipment by puncturing the insulation thereof.

An important object of my invention, therefore, is to eliminate in large measure the undesirable transient waves in transformer equipment referred to, and to produce a new transformer power unit and a new fluorescent tube lighting system which are characterized by their uniformly good wave form, the substantial absence of detrimental high-voltage transients, and by the long life of the tube units employed in such system.

Additionally, appreciable reduction in the iron content required of the transformer unit would result in appreciable savings in the cost of production, as well as in the size of the unit. This reasonably can be expected to enhance appreciably the acceptance of this type of tube lighting equipment beyond even the already assured and established position and acceptance which such equipment occupies in the art.

A further object of my invention, therefore, is to produce a transformer having high leakage reactance characteristics and which is adapted for powering fluorescent tube lighting systems, which transformer is characterized by its extremely small size for rated power output and which requires a minimum of iron content for rated efficiency and rated voltage regulation of the associated load, and which transformer is simple, compact, sturdy and inexpensive, both to produce and to operate, and which at the same time is highly practical and complies fully with all of the requirements of the Fire Underwriters.

Referring now more particularly to the embodiment of my invention depicted in Figure 1,

therein the transformer core is indicated generally at 10. This core consists illustratively of a central, longitudinally extending leg 11, flanked on opposite sides, preferably at equal distances therefrom, by two similar outer legs 12 and 13 extending parallel thereto. Corresponding ends of the outer legs and central leg are closed by similar outer legs or end pieces 14 and 15.

While as has been described, and for purposes of symmetry, and so that the flux courses through the branch magnetic paths to be described, will be substantially equal, I prefer to space the outer legs of similar magnetic proportions equally distant from the central leg 11, it is not absolutely essential that this be done, and it is entirely possible that the spacing or magnetic properties of any or all of the outer legs, as well as the inner leg 11, can be increased or decreased within wide limits. In point of fact, an operable structure can be achieved with the removal of one of the outer legs in its entirety. However, I prefer to construct the core so as to produce the balanced, shell-type transformer illustrated, giving a transformer which is reduced to the smallest possible compass, consistent with good magnetic and electrical characteristics and performance. Intermediate the lengths of the outer legs 12, 13, I provide high leakage reactance magnetic shunts Sh_1 and Sh_2 , respectively, extending towards but short of the central leg 11, forming therebetween air-gaps G_1 and G_2 . Preferably, these shunts, as well as the other parts of the core structure, are constructed of laminated iron material.

The air-gaps G_1 , G_2 are constructed to have a desired and predetermined high reluctance, calibrated in accordance with the admittance of that part of the main flux path illustrated at the left of the shunts in Figure 1, when that main flux path is operating under load conditions. More will be said about this action at a later point in this description.

The shunts have the effect of dividing the openings provided between central and outer legs into two pairs of spaces, one pair on each side of said shunts. In one said space, to the right of the shunts in Figure 1, I provide a primary winding 16, about the central leg 11, which said winding is energized through leads 17 and 18, by a suitable source of alternating-current energy 19.

Since it is desirable to energize the system from the ordinary service mains, which usually are of approximately either 110 or 220 volt rating, and since I desire to operate by tubes at the maximum of 600 volts secondary terminal voltage permitted by the Fire Underwriters for autotransformer-connection, or even at higher voltages when the autotransformer-connection and its resulting copper savings are dispensed with, and general transformer connection resorted to, I construct my transformer of the step-up type, with the effective secondary windings having a substantially greater voltage per turn than does the primary winding.

I provide my transformer with two secondary windings, one in each of the mentioned pair of spaces. The first secondary winding, indicated at 20, preferably is wound, as shown, directly on the primary winding 16, thus effecting material economies in core material and in the total space requirement of the power unit. It is entirely feasible, if desired, however, to elongate legs 11, 12 and 13, and to position the secondary winding 20 at the side of the primary winding, separate therefrom, but within the first pair of spaces as thus elongated as illustrated in Figure 75

5 in which parts corresponding to those of Figures 1 and 2 are indicated by like numerals but with the subscript "a" added.

It is evident that the primary winding in the embodiments shown, is electrically separate and independent of the secondary winding 20, and has no direct electrical connection therewith. This secondary winding 20 is only inductively associated with the primary winding 16. Additionally, with the secondary winding 20 being mounted on central leg 11 and on the same side of shunts Sh_1 , Sh_2 as is the primary winding 16, the shunts exert no current-limiting effect when the arc strikes across the tube load of this secondary winding. A power-factor correcting condenser C advisedly is employed where it is desired to restore the system power-factor to approximately unity. Reliance also is placed upon this condenser for current-limiting action in the load circuit of secondary coil section 20, as is more fully described hereinafter.

20 In the secondary pair of spaces, a second secondary winding 21 is provided, on the opposite side of shunts Sh_1 , Sh_2 from the primary winding 16, and this secondary winding 21 is connected in autotransformer connection across the primary winding 16. Circuits may be traced from primary winding 16 to secondary winding 21 as follows: from the left-hand end of winding 16 in Figure 1, down through lead 17 to junction 22; thence through lead 23 to the right-hand end of secondary winding 21 in Figure 1, to the left across this secondary winding to the left-hand terminal thereof, then down through lead 24 to tube T_2 , lead 25, junction 26, and up through lead 18 to the right-hand end of primary winding 16.

40 It may be pointed out at this time that secondary winding 20 directly energizes tube T_1 and condenser C through leads 27 and 28. A circuit may be traced from the left-hand end of winding 20 in Figure 1, lead 28, tube T_1 , condenser C and lead 27 back to the right-hand end of secondary winding 20. The source 19 of alternating current electrical energy energizes winding 16 through a circuit of periodically reversing direction, traced as follows for a given current half-cycle: to the right in Figure 1 from source 19, up through lead 18, to the right-hand end of winding 16, across the winding and back through lead 17 to the left-hand end of the power source. During the next successive current half-cycle, of course, the direction of current flow is just the reverse of that traced.

55 It is interesting, as well as highly instructive, to consider at this point, the manner in which the primary flux courses the flux paths through the illustrative magnetic core which has been described. For this purpose, consideration is given to an instantaneous direction of flow of primary current through winding 16 such that the primary flux developed thereby courses to the right in Figure 1 along central leg 11 from winding 16. When the flux reaches end piece 14, it courses along two individual paths of low reluctance, one said path sequentially including end piece 14, core leg 12, and end piece 15 to leg 11. Similarly, the second flux path sequentially includes end piece 14, core leg 13, end piece 15 to leg 11.

65 Since the flux seeks paths of least reluctance, the high reluctance magnetic by-passes Sh_1 , G_1 and Sh_2 , G_2 , respectively are in large measure avoided, and only an extremely small part of the flux courses across these shunt paths, to the central leg 11, and back to primary winding 16.

As has been stated, by far the greater part of the flux courses along the two individual paths of low reluctance; which paths reunite at the left-hand end of inner core leg 14, and return along leg 11 to primary winding 16. It will be noted that at all times the full quantity of primary flux links the secondary winding 20, and develops a rated high voltage therein. Similarly, before the secondary tube load T_2 across winding 21 has been energized as a result of the arc striking thereacross, either initially or during any current half-cycle, substantially the full primary flux links winding 21, inducing a high voltage therein.

Because of the high secondary voltages employed, as has been stated hereinbefore, the terminal voltages of the secondary windings, impressed directly across the electrodes of the associated tube loads, bring these tubes to a high degree of excitation so that after the passage of but a comparatively few cycles of current flow, the arcs in the several tubes ignite, and steady operating conditions maintain.

As soon as the tube load T_1 becomes energized, a back magneto-motive force is developed in winding 20, tending to buck the primary flux from 16. Because no magnetic by-pass is provided between windings 20 and 16, flux continues to course the main magnetic core.

When the arc strikes across tube T_2 , the back magneto-motive force developed in winding 21 is found to afford considerable reluctance to the coursing of the primary flux along the path encircled by winding 21. Always seeking the path or paths of least reluctance, therefore, and since the magnetic by-passes Sh_1 , G_1 , Sh_2 , G_2 are now of lower reluctance than the main path interlinking winding 21, the flux coursing the individual magnetic paths, travels down shunt leg Sh_1 and across air-gap G_1 , and up shunt leg Sh_2 and across air-gap G_2 , respectively, directly back to primary winding 16, and in large measure bypasses winding 21. At such times when the arc is struck across tube T_2 and the tube remains energized, the shunts because of their design, permit only enough primary flux to interlink winding 21 to provide sufficient voltage and current to ensure energization of tube T_2 .

During the next subsequent and alternate half-cycle of primary current flow, the direction of coursing of the primary flux is just the reverse of that which has been traced. From winding 16, the flux courses along leg 11 to the left in Figure 1. Very small quantities of flux course, across air-gap G_1 , up shunt Sh_1 , to the right along leg 12 and down end piece 14, leg 11, back to winding 16; and down across air-gap G_2 , shunt leg Sh_2 , to the right along leg 13, up end piece 14, leg 11, and back to winding 16. By far the greater part continues to the left along leg 11, interlinking winding 21 and inducing a high voltage therein. At end piece 15, the main flux separates into two substantially equal branches. The flux courses, in part, up end piece 15, to the right in Figure 1 along leg 12, down end piece 14, to leg 11; and, in part, courses down end piece 15, to the right in Figure 1 along leg 13, and up end piece 14 to leg 11. There the flux reunites and courses along leg 11 back to winding 16, interlinking winding 20. When the arc initially strikes across tube T_1 , and when it strikes anew in each current half-cycle, the back magneto-motive force developed thereby has relatively little effect on the primary flux, for the reasons pointed out hereinbefore.

However, as soon as the arc strikes across tube 75 may 16 but is only inductively associated there-

T_2 , a back magneto-motive force is developed in coil 21 in a direction contrary to and bucking the primary flux, so that the main flux path, previously of low reluctance, now becomes one of comparatively high reluctance as compared to the high leakage shunt paths including shunts Sh_1 and Sh_2 . Since the flux always seeks a path or paths of least reluctance, by far the larger part of the primary flux at this time courses across two shunt paths, effectively by-passing in large measure the secondary winding 21. Flux courses, in part, up across air-gap G_1 , Sh_1 , to the right along leg 12, down end piece 14, and back through leg 11 to winding 16; and courses, in part, down across air-gap G_2 , Sh_2 , to the right along leg 13, up end piece 14, and back along leg 11 to winding 16. Only a small amount of the primary flux, sufficient to maintain the voltage and current required for tube T_2 , continues coursing the length of leg 11, interlinking winding 21 and splitting at end piece 15 into two branches which course back to winding 16 through legs 12 and 13 in the manner previously discussed.

Toward the end of each half-cycle primary 25 charging flux, as the value of the flux decreases, the induced voltage drops to a point where the arc across the associated tube load extinguishes, whereupon the back magneto-motive force at once disappears. The reluctance of the main 30 flux paths drops to its former value, so that the flux no longer courses the high leakage reactance shunt paths, but resumes coursing the main flux paths until at such times as the arcs are re-ignited.

35 Tubes T_1 and T_2 are of the usual fluorescent gas discharge type in that they are designed so that a large part of the input energy is converted to what is known as the resonance line, 2537 Å., in the ultra-violet portion of the tube spectrum. 40 This radiation serves to excite the particular photoelectric coating or lining, known as a phosphor, provided on the interior walls of the tube, and which energized, gives rise to a desired characteristic radiation. As stated, the tubes may either be 45 the available hot-cathode tubes now on the market, with short-circuited cathodes to ensure unipotential electrodes, or cold-cathode tubes designed especially for the particular use to which 50 they are to be put.

55 Since secondary winding 20 from a magnetic standpoint is disposed on the same side of shunts Sh_1 , G_1 , and Sh_2 , G_2 as is winding 16, and is in only inductive association with the primary winding, the transformer, certainly within the saturation limits of the iron core thereof, exercises no appreciable control action on the build-up of current flow across the tube load of negative resistance characteristics. However, since the predominately inductive nature of the load across 60 source 18 requires the use of a balancing capacitative reactance to restore somewhat the system power-factor, this capacitative reactance, in the form of high capacitative condenser C , is disposed across secondary 20, in series with tube T_1 ; and use is made of its high reactance to maintain the current across this tube within the required safe limits. It is for this reason that it is unnecessary to dispose a high leakage reactance shunt or shunts between windings 16 and 20. This condenser, for example, may have a capacity ranging from 1.5 to about 1.75 microfarads.

In operation, probably because the winding 20 is not in autotransformer connection with primary 70 16 but is only inductively associated there-

with, disturbances arising in one of the secondary circuits are substantially damped from the other secondary circuit. Thus, in a lighting system according to our invention, all substantial tendency towards cumulative resonating effects or transient disturbances between transformer secondary windings is substantially suppressed, giving improved light emission and prolonged tube life.

In Figure 3, for example, a graph is shown of one cycle of the current flow on the T₁ or condensor side of the transformer system, while in Figure 4 is displayed one cycle on the T₂ or inductive side of the line. In the latter case, the wave form is nearly sine-wave in nature. In each case, the abscissae are current values, while the ordinates are units of time. Substantially all ripples at the striking and extinguishment of the arc are avoided by directly shunting tubes T₁ and T₂ by small, radio frequency condensers 23, 30, respectively, of approximately .005 or .006 microfarads capacity.

I have found that my new construction makes it possible to retain substantially all of the advantages of the high leakage reactance transformer power units for fluorescent tube lighting, such as quick starting and stable operating characteristics, even under extreme weather conditions which may prevail, long tube life, good voltage regulation, economy both in first cost and in operation and maintenance expenses, simplicity, sturdiness and ruggedness, while at the same time achieving a thoroughly practical power unit and associated system in which the iron content is reduced to a minimum with no decrease in good voltage regulation. The resulting unit is small, compact, requires a minimum of space and conveniently is mounted, for example, directly on the reflector of a tube assembly, and has a minimum number of external connections.

The new system which I produce has high system power factor, so that energy consumption, and hence costs, is reduced to a minimum, and waste power, dissipated in heat, is negligible. Transient harmonics of any appreciable or detrimental value are substantially eliminated, so that a smooth, almost ideal wave form results, with no detrimental over-voltages, and so that both the new transformer and system comply fully with the requirements of the Fire Underwriters.

Attributable in large measure to the substantial absence of high voltage harmonics and the consequent presence only of rated voltages, the tube life is greatly prolonged, and the electrode material thereof is unharmed by sputtering or similar phenomena. Little if any electrode material is volatilized off and deposited as an opaque lining on the tube walls, so that light transmission remains substantially constant throughout the normal life of the tube. Similarly, there is no occlusion of the gas content of the tube by any such deposited coating, as a result of which there is a substantial absence of the detrimental phenomenon known as "hardening." No appreciable decrease in the electron-emitting qualities of the electrodes is experienced during the rated life of the tubes. These several last-mentioned advantageous features contribute to light emission of substantially uniform quality throughout the useful life of the tubes.

As many possible embodiments may be made of my invention and as many changes may be made in the embodiment hereinbefore set forth, it is to be understood that all matter described

herein is to be interpreted as illustrative, and not in a limiting sense.

I claim:

1. A transformer, comprising in combination, a primary winding and two secondary winding coil sections only, with one secondary coil section tightly coupled with said primary and the other secondary coil section loosely coupled therewith; a main magnetic core linking said primary winding and two secondary winding coil sections; magnetic shunt core means positioned between the primary winding and said loosely coupled secondary coil section; electrical connections between said primary winding and at least one of said secondary winding coil sections providing an autotransformer connection; and terminal connections for two loads, one including one secondary winding coil section and the other including the other secondary coil section, at least one of said terminal connections also including said autoconnected primary winding.

2. A transformer, comprising in combination, a primary winding and two secondary winding coil sections only, with one secondary coil section tightly coupled with said primary and the other secondary coil section loosely coupled therewith; a main magnetic core linking said primary winding and two secondary winding coil sections; magnetic shunt core means positioned between the primary winding and said loosely coupled secondary coil sections; terminal connections for two loads, one including one secondary winding coil section and the other including the other secondary coil section, at least one of said terminal connections also including said autoconnected primary winding.

3. A transformer comprising in combination, a magnetic core; three windings only positioned on said core and comprising a primary winding and two secondary windings, with one of said secondary windings spaced from said primary winding and loosely coupled therewith and the other secondary winding positioned on top of the primary winding and closely coupled therewith; magnetic core shunt means positioned between the primary winding and said spaced secondary winding; terminal connections for two loads, one including one secondary winding and the other including the other secondary winding; and electrical input connections to said primary winding.

4. A transformer comprising in combination, a shell-type core having a central leg and two outer legs; three windings only positioned along the central leg of said core and comprising a primary winding and two secondary windings, with one of said secondary windings positioned on one side of said primary winding, being spaced therefrom and loosely coupled therewith and the other secondary winding positioned on the other side of said primary winding and tightly coupled therewith; magnetic core shunt means positioned between the primary winding and said loosely coupled winding; and terminal connections for two loads, one including one secondary winding and the other including the other secondary winding.
